UNITED STATES PATENT OFFICE.

BERNARD DONAHUE, OF YONKERS, NEW YORK.

DESIGN FOR AN INSERTIBLE JAW FOR WRENCHES.

SPECIFICATION forming part of Design No. 19,412, dated November 12, 1889.

Application filed October 15, 1889. Serial No. 327,127. Term of patent 14 years.

To all whom it may concern:

Be it known that I, BERNARD DONAHUE, a citizen of the United States, residing at Yonkers, in the county of Westchester and State of New York, have invented and produced a new and original Design for an Insertible Jaw for Wrenches, of which the following is a specification.

This design has for its object to provide a novel insertible jaw for wrenches; and the leading feature of the design consists in a block provided on its upper surface with diagonal serrations and on its lower side with an angular shank, leaving a straight shoulder at each side.

The design is illustrated by the accompanying drawing, in which the figure is a perspective view of the insertible jaw on an enlarged scale.

In the drawing, the numeral 1 indicates the block, provided on its upper side with serrations 2, running diagonally with respect to the straight sides 3. The lower side of the block is furnished with a shank 4, angular in cross-section, leaving a straight shoulder 5 at each side.

Having thus described my design, what I claim is—

The design for an insertible jaw for wrenches, substantially as shown and described.

In testimony whereof I have affixed my signature in presence of two witnesses.

BERNARD DONAHUE.

Witnesses:

JAMES L. NORRIS,
JAMES A. RUTHERFORD.
